WALL MOUNTED AIR HUMIDIFIER OR THE LIKE

Hans Rudolf Stoop, Zug, Switzerland, assignor to
Defensor AG, Zurich, Switzerland, a corporation
of Switzerland

Filed Apr. 4, 1969, Ser. No. 16,580

Claims priority, application Switzerland Oct. 18, 1968

Term of patent 7 years

Int. Cl. D23—04

U.S. Cl. D23—147

FIG. 1

FIG. 2

FIG. 3

FIG. 4

FIG. 5

FIG. 6

FIG. 7

FIG. 1 is a perspective view of the air humidifier embodying my new design;

FIG. 2 is a side view thereof;

FIG. 3 is a top view thereof;

FIG. 4 is a front view thereof;

FIG. 5 is a bottom plane view thereof;

FIG. 6 is a rear view thereof; and

FIG. 7 is a fragmentary view of the perforated covering panel for the top, sides and bottom of the air humidifier.

The undisclosed remaining side of the air humidifier is substantially identical to the side shown in FIG. 2.

I claim:

The ornamental design for a wall mounted air humidifier or the like, substantially as shown and described.
